UNITED STATES PATENT OFFICE.

TROY L. PARKER, OF CHICAGO, ILLINOIS.

PHOTOMETER.

1,276,259.

Specification of Letters Patent. Patented Aug. 20, 1918.

Application filed November 15, 1915. Serial No. 61,496.

To all whom it may concern:

Be it known that I, TROY L. PARKER, a citizen of the United States, residing at Chicago, in the county of Cook and State 5 of Illinois, have invented a certain new and useful Improvement in Photometers, of which the following is a specification.

My invention relates to improvements in photometers, and has for one object to provide a new and improved meter for measuring the intensity of illumination. Another object is to provide means for directly indicating by observation of the user the suitable time for exposure of photographic 10 films and the like. Another object is to provide a photometer which shall be compact, accurate and self-contained, and which can be used by the operator to get readings in any suitable way without the necessity of 15 any additional apparatus or special preparation. Other objects will appear from time to time in the specification. My invention is illustrated in the accompanying drawings wherein,

25 Figure 1 is a side elevation showing the photometer in the extended position ready for operation.

Fig. 2 is a longitudinal section on an enlarged scale.

30 Fig. 3 is a section along the line 3—3 of Fig. 1.

Fig. 4 is a side elevation of the shutter itself.

Fig. 5 a longitudinal section through the 35 shutter showing a modified arrangement.

Fig. 6 is a section along the line 6—6 of Fig. 5.

Like parts are indicated by similar letters in all the figures.

40 A is a cylindrical barrel. It is necked down at one end as at A¹ to an internal diameter slightly smaller than the internal diameter of the remainder thereof. Immediately adjacent the necked down portion 45 and projecting from the cylinder barrel proper is a knurled or roughened collar A². The wall of the cylinder A is provided with a triangular aperture A³ having one side parallel with the axis of the cylinder.

50 Along that side is arranged a scale A⁴ calibrated as indicated in time intervals, in this case preferably calibrated for time intervals necessary for the proper exposure of a photographic film, though obviously it might 55 be calibrated on any suitable basis. The triangular aperture, it will be noted, in-

creases toward the lower end of the cylinder where it is bounded by a side wall at right angles to the long calibrated wall. The third side wall is a spiral as indicated.

60

B is a hollow tube slidably mounted in the necked down portion of the cylinder A¹, the bearing surface between the two being sufficient to hold the tube at all times and in all positions in parallelism with the cylinder 65 and to prevent rocking or tipping of the tube with respect to the cylinder. B¹ is a truncated conical eyepiece provided at its inner end with a reduced cylindrical portion B² engaging the interior of the tube B 70 and held therein by any suitable means not here specifically indicated. This reduced portion has the cross wall B³ apertured for vision at B⁴ on the common axis of cylinder and tube. B⁵ is a disk perforate at B⁶ in 75 line with the perforation B⁴. This disk is thrust into the opposed end of the tube B and expands it as indicated sufficiently to prevent complete withdrawal of the tube from the reduced portion of the cylinder. 80

C is a cylindrical shutter. It is rotatably mounted inside the cylinder A. It is provided at its bottom with knurled or roughened collar C¹ adapted to project upwardly beyond the surface of the cylinder A. The 85 bottom of this shutter is closed as at C² and contains a disk C³ upon which is a suitable object such as the cross C⁴. In my preferred form the disk is white and the cross black, so as to be clearly visible. The effective edge of the shutter is a spiral as indicated at C⁵. Thus immediately above the collar C¹ the shutter is completely cylindrical. Just above that point it is cut away and its effective width measured on an arc 90 of the cylinder gradually decreases toward its upper end where the shutter is just wide enough to completely close the upper end of the aperture in the cylinder A. This narrow extension of the shutter is provided with a lug C⁶ which engages a groove C⁷ in the interior of the cylinder A whereby the shutter when once thrust into the cylinder, is held therein by the yielding pressure of the shutter, which yieldingly holds the lug 100 105 in the groove.

D is a translucent cylinder or screen. It is carried by and in a sense forms part of the shutter and preferably is located within it though it might abut against it if that 110 prove desirable. This cylinder is more or less opaque, and tends more or less to ob-

struct the passage of light rays into the interior of the instrument. This cylinder closes up and keeps the sleeve always closed so as to prevent too intense illumination and 5 so as to control the operation of the device.

It will be evident that while I have shown in my drawings an operative device, still many changes might be made in size, shape and arrangement of parts without departing 10 from the spirit of my invention.

The use and operation of my invention are as follows:—

The operator, who expects either to measure the intensity of the light where he stands 15 or else to determine the time during which he must expose his photographic film or plate in order to take a picture, starts with the eye-piece in the position shown in dotted lines in Fig. 1. At that time the shutter 20 would preferably be in such position as to completely close the triangular aperture in the cylinder. The operator then draws the eyepiece and tube out into the position shown in Fig. 2. He rotates the shutter until 25 the aperture in the cylinder is completely open. He then approaches the place at which he wishes to make the determination. If he is going to take a picture, he wants to find the intensity of the light falling upon 30 the object to be photographed, and so he approaches the object which he wishes to photograph. He stands facing the brightest light with the instrument in his hand and points it toward the light, holding it in a 35 substantially horizontal plane with the aperture in the cylinder open upwardly so that light falls in the cylinder. He applies his eye closely to the eyepiece and looking through, sees the black cross on the white 40 ground. By rotating the shutter in a clockwise direction, he gradually closes the triangular aperture in the wall of the cylinder, thus decreasing the amount of light falling on the object cross. This rotation will be 45 continued until the cross becomes invisible, or barely visible as suits his eye. At that point he stops rotation of the shutter, and reads on the scale on the cylinder the time for exposure indicated where the diagonal 50 wall of the shutter crosses the scale. It will be understood that the eye is closely applied to the eyepiece in order to completely exclude the light around the eyepiece. It will also be understood that if for any reason the 55 operator can not himself go to and stand by the thing which he wishes to photograph, he will still be able to get a reading by going to a place where the light conditions appear to be about the same as those prevalent about 60 the object to be photographed.

For the sake of illustration, we will assume that the operator has made his observation and he finds that the shutter has moved until the boundary wall occupies the position shown in dotted lines in Fig. 1. That

wall cuts the index side between ten and twenty five seconds. He makes the necessary mental calculation and reads say fifteen seconds. This is the time he must expose his film if his lens is open at a sixteen diaphragm. If the lens is open wider or not so wide, he must change the time accordingly. In other words, I have selected the sixteen diaphragm because the sixteen opening is common to a number of lens opening 75 or aperture scales. If instead of wishing to operate at sixteen, he wishes to operate at a larger aperture, say, eight, which on the United States scale means a diaphragm of twice the effective opening, he will divide 80 his reading of fifteen seconds by half, expose his film seven and a half seconds. If, on the other hand, he wishes to close down to one half the opening, he will multiply his reading by two and expose his film in fifteen 85 to thirty seconds. It will be understood that direct sunlight must not be allowed to impinge upon the object disk, and the operator by carefully manipulating the device, can avoid this. However, in order to insure that 90 only direct modified illumination shall be allowed to act upon the disk, I provide the translucent cylinder within the shutter. This may take the form of paper, glass, celluloid or any other suitable material as indicated. It 95 permits the light to pass through, but does not permit the free unobstructed sunlight to fall through to the disk even if the instrument were improperly held. It will be understood that for different purposes, cylinders of different quality might be used. For 100 very bright work in the tropics, a very dark colored cylinder would be used. For work in dark places, a lighter cylinder might be used. It will be understood that different 105 types of photographic work and plates and films having different subjects are in use, and my device may be conveniently adapted for such purposes by using different kinds of screen cylinders, so that the reading is 110 modified according to the peculiar uses to which any particular instrument is to be put. It will be understood that the size of the apertures in the two disks or transverse walls at either end of the eyepiece carrying tube 115 may vary. It is desirable, however, that their proportionate sizes be such that the line of sight as the operator has his eye in the eyepiece and looks inwardly toward the object disk, will not be appreciably interfered with by the presence of the inner disk. That is to say, the inner disk must 120 preferably be provided with an aperture larger than the eyepiece aperture so that the operator will not be conscious of its presence. This apertured disk serves a double purpose. It expands the tube to prevent its withdrawal, but more than that it protects the walls of the eyepiece carrying tube 125 against illumination by light rays which 130

would otherwise be reflected into the eye of the operator, and thus interfere with the accuracy of the reading made by him. It will be noted that the aperture through the farther disk is provided with counter sunk or conical sides, so that there may be no possible chance of any reflection of light rays into the eye of the operator by the wall of the hole. The inner edge is sharp and cannot therefore well reflect any appreciable quantity of light.

The photometer is thus divided into an illumination chamber with a light window in the wall thereof, a visual object therein, and means for controlling the effective opening of the window, and an eyepiece removed from the illumination chamber but connected to it by a light-tight casing which casing is provided with means for preventing reflection of light from the illuminating chamber into the eyepiece by the walls thereof, thus the only light rays reaching the eye of the operator must come direct from the illumination chamber and cannot be reflected by the walls of the connection into the eye of the operator.

It will be understood that preferably the entire interior of the instrument will be black, of a dead, dull finish, in order that if by any chance any uncontrolled light rays do enter, they will be absorbed and not reflected. The shield which may take the form of the perforate partition or of the cylinder in the shutter being interposed in both cases between the object and the source of light, operates in part to prevent the impingement on the eye-piece of any light rays except those reflected from the object, and it will be observed that the perforate partition and the colored cylinder are for this purpose at least equivalent since whatever may be their separate functions, each one of them will have this specific function.

While the apertured partition and the translucent cylinder or diaphragm are equivalent for some purposes it is evident that under certain circumstances it is desirable to use them both in the same machine and under some circumstances they would coöperate to produce the same result. Most cylinders of different color or different thickness would very obviously have varying effects on the reflected light rays and on the intensity of illumination so that by changes in the size of the aperture in the plug or wall and by changes in the color of the thickness of the diaphragm, a desired combination may be obtained.

I claim:

1. A photometer comprising a single opaque visual object, means for controlling the illumination thereof, an eye piece removed from said object and means for preventing the entrance into said eye-piece of any light rays except those coming directly from the object.

2. A photometer comprising a single opaque visual object, means for controlling the illumination thereof, an eye-piece removed from said object and means for preventing the entrance into said eye-piece of any light rays except those coming directly from the object, said means comprising an apertured partition interposed between the eye-piece and the object.

3. A photometer comprising a single opaque visual object, an illumination chamber in which it is contained, means for controlling the illumination of the object by varying the amount of light entering the chamber, an eye-piece removed from the chamber and means for excluding from the eye-piece any light rays except those reflected by the object.

4. In an optical instrument a supporting sleeve, a tube slidable therein the sleeve being provided with a bearing for the tube, an eye piece mounted in one end of the tube larger than the bearing in the sleeve, a perforated plug mounted in the other end of the tube larger than the normal interior diameter of the tube and adapted to expand the tube to an outer diameter larger than the diameter of the bearing the perforations in the eye piece and in the plug being concentric and in line with the axis of the tube.

5. In a photometer a single illumination chamber, an opaque visual object therein the wall of the chamber being perforated, a shutter mounted for movement within the chamber across such perforation and a translucent diffusing screen carried by said shutter mounted for movement within said chamber and adapted always to extend across that part of the perforation in the chamber wall which may be uncovered by the shutter and an eye piece in line with the visual object.

In testimony whereof, I affix my signature in the presence of two witnesses this 10th day of November, 1915.

TROY L. PARKER.
